UNITED STATES PATENT OFFICE

CHARLES L. ROSS, OF WASHINGTON, DISTRICT OF COLUMBIA

FIREARMS

Application filed October 14, 1930. Serial No. 488,650.

This invention relates to firearms and particularly to breech mechanisms including extractors.

The present application is a substitute for, and in part a continuation of, my allowed application Serial No. 358,544, filed April 27, 1929.

The invention is intended for use in firearms, generally, but will be described as developed for use in a semi-automatic shoulder rifle, i. e., one which fires a shot and reloads automatically each time the trigger is pulled. The invention is suitable for use in machine guns and hand actuated repeating rifles, and in firearms generally wherever there can be used an action slide which will carry the necessary cams.

In the particular embodiment to be described the breech block moves transversely to the bore and this arrangement is preferred, but may be departed from within the broad scope of the invention. The parts, including the breech block, function by means of an action slide driven by any suitable means, such as a gas piston. The action slide is formed with cams which actuate the breech block and other cams which actuate a star wheel, the latter in two steps of rotary motion. The first and larger step occurs in the rearward excursion of the slide immediately after the cartridge is fired; the second occurs near the conclusion of the return motion.

The invention may be used with either rimmed or cannelured cartridges, but because the cannelured cartridge presents the more difficult problem, an embodiment for handling this type of cartridge is chosen for illustration.

Hence, referring to an extractor for cannelured cartridges, there is an extractor lever, which at its lower end has a lug confined in a slot so arranged that the nose of the extractor may move in a four-sided path, first radially outward to engage the cartridge case, then a swinging motion to the rear to extract, then radially inward to release the case, and then a swinging motion forward to the initial position. This extractor is actuated by two sets of cams turned by the star wheel and goes through its first three motions during the

first motion step of the star wheel and its fourth motion during the second motion step of the star wheel. For rimmed cartridges the radial motions of the extractor may be dispensed with.

This extractor frees the case from the chamber and may or may not be sufficient to throw the case clear. Other means are normally provided to carry the case rearward and eject it at the end of such motion. These take the form of a rammer having a lost-motion connection with the action slide, and a spring connection therewith so arranged that the action slide urges the rammer yieldingly to the rear, but on its return or forward motion actuates the rammer positively. The rammer has a latch which engages the cartridge case. When the action slide starts back it stresses the rammer spring until the extractor functions to free the cartridge. When the cartridge case is freed, the rammer, then spring-impelled, jerks it to the rear. The spring urged rearward motion ends with an impact which throws the cartridge case clear and thus ejects it.

Thus the invention is characterized by a short travel extractor operated independently of but in timed relation with the breech block, in conjunction with spring-actuated long travel means for further withdrawing and ejecting the case. This spring-actuated means serves also as a positively actuated rammer, which acts, on the return motion of the action slide, to feed and chamber the next cartridge. This arrangement, in conjunction with a transversely moving breech block produces an unusually compact and rugged mechanism of few parts. In the example illustrated the breech block is positively actuated in one direction and is closed by a spring. Other arrangements are possible within the scope of the invention. Certain features of the invention may be used with other known types of breech block. In the broadest aspects of the inventive concept any breech block capable of actuation by a longitudinally moving action slide may be availed of.

The preferred embodiment of the inven-

tion is illustrated in the accompanying drawings, in which

Fig. 1 is a section on the vertical plane through the axis of the barrel, showing a portion of the chamber, the breech block, extractor, rammer, the portion of the action slide and cam mechanism in loaded position ready to fire.

Fig. 2 shows the same parts after firing, the action slide having started back far enough to open the breech and the extractor having moved radially upward and started to swing to the rear.

Fig. 3 shows a later phase, the extractor having moved radially downward and the rammer having, under spring impulsion, jerked the case to the rear.

Fig. 4 shows the position of the parts when the action slide has moved still further to the rear.

Fig. 5 shows the position of the parts when the action slider has nearly reached its forward position and the star wheel actuated cam is about to free the extractor so that the rammer may return the extractor to its initial position.

Fig. 6 is a plan view of the star wheel and connected cams in the position of Fig. 1.

Fig. 7 is a view partly in vertical section through the axis of the bore, showing how the rammer is connected with the action slide.

Fig. 8 is a plan view showing the connection of the rammer with the action slide, and (in dotted lines) the relation of the star wheel and its cams to the above named parts.

Fig. 9 is a vertical axial section through the breech block.

Fig. 10 is a front elevation of the breech block.

Fig. 11 is an elevation of the right hand side of the breech block partly broken away.

Fig. 12 is a perspective view looking at the rammer from the left and rear.

Fig. 13 is a perspective view looking at the rammer from the right and rear.

Fig. 14 is a view similar to Fig. 1, but showing the full length of the action cams and the position of the breech block actuating spring.

The action slide is bifurcated or forked, as viewed in plan (see Fig. 8) and is indicated generally by the numeral 16. Each of the two tine portions is formed with a cam surface 17, the two cam surfaces being identical with each other. Each coacts with a corresponding beveled face 18 at the lower bifurcated end of the breech block, indicated generally by the numeral 19. The breech end of the barrel appears at 21 and as illustrated in the drawings is formed with a vertical slot in which the breech block 19 is guided to move vertically. The breech block may, if preferred, be otherwise guided. The breech block is forced upward by the cam 17 and

is returned by any suitable means. In the example illustrated, a bow spring 20 is used (see Fig. 14). This spring 20 seats in a recess 30 in the breech block (see Figs. 8 and 10) and in a recess 40 (see Fig. 14) formed in the breech end of the barrel.

The chamber appears at 22. Mounted on the left hand face of the left hand bifurcated portion of action slide 16 are two cam elements 23, 24, which coact with round lugs 25 on a star wheel member 26. The star wheel 26 is formed integrally with a rotary member having journals 27, 28, which turn in suitable bearings, illustrated in the drawings. Between the journals 27, 28, the rotary member is provided with two sets of cams. The number of cams in the two sets are the same and conform to the number of arms on the star wheel. A three armed star wheel is preferred. These cams are shown at 29 and 31 and conjointly actuate the extractor.

The extractor consists of a lever member 32 having a nose 33 at its upper end which is adapted to enter the cannelure 34 at the rear of the cartridge case 35. The extractor 32 has a tongue 36 at its other (lower) end which is confined in a slot 37 in a plate 38 which underlies the action slide. The extractor lever 32 is provided at a short distance below its upper end with a transverse lug 39 which serves a dual purpose. Its forward end serves as an abutment or shoulder against which the cams 29 act to raise the lever 32, that is, to move it upward so that it engages the cannelure 34. It also serves as a stop engaging the forward face of the breech block 19 to prevent the extractor lever 32 from swinging to the rear until the breech block 19 has risen to its upper or open position. In such position a notch 41 formed in the forward face of the breech block offers clearance for the member 39 and permits the extractor lever 32 to move to the rear. This rearward motion is produced by one of the three cams 31 engaging a boss 42 formed on the front face of the lever 32 for this purpose.

Formed in the right hand portion of the bifurcated action slide 16 is a slot 43, and guided in this slot is a slider 44 whose length is less than the length of the slot 43 so as to permit limited lost motion between slider 44 and the action slide 16. A compression spring 45 is mounted on a guide rod 46 and is confined between a spring seat 47 on the action slide 16 and a spring seat 48 on the slider 44. The slider 44 is connected by member 49 with a rammer 51 which is provided with a resilient latch nose 52 also intended to engage the cannelure 34 in the cartridge. It will be observed that the nose 33 of the extractor engages the cannelure at the lower side of the case and that the latch 52 engages the cannelure at the right side of

the case, so that interference does not occur.

The latch nose is received in a cut 53 formed in the breech block for that purpose, and the rammer has an upward extending lug 54 which is received in a cut 55 in the breech block. It will be observed that the breech block descends after the rammer has chambered the cartridge and rises before the rammer moves to the rear. Consequently the recesses 53 and 55 are formed only in the forward face of the breech block and do not extend through this from front to back.

The firing pin is shown at 56. It is urged to the rear by a spring 57 and is retained by a pin 58 which works in a slot 59 of such length as to permit the necessary motion of the firing pin.

The form of the parts will be clear from an examination of Figs. 9 and 14 of the drawings.

The operation of the mechanism is as follows:

Assume that a cartridge is in the chamber and the breech block is in its lower position (Fig. 1). The firing pin is driven forward, by any suitable means, such as a hammer, (not shown), which strikes the rear end of the firing pin. In an automatic arm the firing of the cartridge would itself cause the action slide to move to the rear. Any known mechanism might be used, but I contemplate the use of a gas cylinder and piston, the cylinder being connected to the bore of the barrel near the muzzle, so that just as the bullet left the bore gas pressure would be admitted to the cylinder, and acting upon the piston, would force the piston and connected slide to the rear. This is a familiar expedient in automatic firearms; and its illustration is deemed to be unnecessary, particularly as any equivalent mechanism might be substituted within the scope of the present invention.

As the action slide moves to the rear the cams 17 engage the surfaces 18 and force the breech block 19 upward. Before the breech block 19 rises far enough to open the rear of the chamber and permit extraction, one of the lugs 25 on the star wheel will be struck by the rear end of the cam 23. This will rotate the star wheel, causing cam 29 to raise the extractor lever 32, and move it radially upward until its nose 33 engages in the cannelure 34. The continued rotation of the star wheel will then cause one of the cams 31 to engage the surface 42 and swing the extractor lever 32 to the rear (see Fig. 3). Lug 39 thus enters notch 41. At about the time the rearward motion of lever 32 is completed, the cam 29 clears the lug 39 on the extractor, allowing this to move downward. This downward motion is assisted by a slight downward motion of the breech block 19, provided for in the form of the cam 17.

It will be observed that the rearward motion of the action slide stresses the spring 45

in compression, but until the cartridge case 35 has been forced to the rear, the spring 45 will be merely stressed and the rammer 51 will remain at rest in engagement with the cartridge case. As soon as the cartridge case 35 has been freed by the extractor 32 the spring 45 will force the rammer to the rear, carrying the cartridge case 35 with it. This rearward motion carries the case clear of the barrel. Motion is suddenly arrested when member 44 collides with the end of slot 43. Since lug 54 engages only the lower portion of the rear end of case 35 (see Fig. 5) the case tumbles upward and is thrown clear.

The rotation of the star wheel mechanism ceases when two of the lugs 25 engage the straight top surface of the cam 23 (see Figs. 3 and 4). In the position of Fig. 4 the breech block 19 has been lowered far enough to carry the extractor 32 to its lowermost position. The action slide is returned to its forward position by any means such as a spring (not shown).

In its forward motion the slider 44 is at the rear end of the slot 43 and consequently moves forward with the action slide. The rammer picks up a cartridge from the magazine (not shown) in the usual manner, and carries the cartridge forward with it, inserting it in the chamber 22 when the slide approaches its forward position (see Fig. 5). The lower rear lug 25 on the star wheel 26 will be struck by the cam 24 and rotated to the position of Fig. 1. This motion carries the tip of the cam 31 above the upper limit of the boss 42 so that the rammer 51, upon striking the upper end of the extractor lever 32, will swing this forward. This forward motion causes the lug 39 to clear the slot 41 and allows the breech block 19 theretofore held open by the lug 39, to drop to its closed position under the urge of the spring 20. This completes the cycle of motion.

It will be observed that the star wheel is formed with three arms and is turned one-third of a revolution for each shot. Thus the three pairs of cams 29, 31, function successively, each pair of cams functioning for one shot in three.

As previously suggested, the invention is not limited to the specific embodiment illustrated but may be variously modified to accord with the specific construction of the firearm with which it is used. While I suggest, and prefer, that the action slide be automatically actuated, it may be manually or otherwise actuated, without departure from the invention.

The device illustrated is believed to be of peculiar utility because it combines with a sliding breech block a reciprocating rammer, which not only feeds and chambers the cartridge but also withdraws and ejects the fired cartridge after the initial extraction has been

performed by the four motion lever extractor. This construction has a peculiar advantage in small arms, particularly shoulder rifles, because the action can be made much shorter than it is possible to make a bolt action, commonly used in automatic small arms. It will be observed that the extractor is smooth and positive in its action.

The use of a bifurcated transversely sliding breech block in conjunction with a rammer mechanism is peculiarly desirable because the breech block rises clear of the rammer mechanism before the extractor functions to permit the rammer to withdraw the cartridge. Furthermore, there is a very useful interrelation between the extractor, the rammer and the breech block, the extractor acting to hold the breech block open until the rammer has chambered the cartridge, and in so doing, has shifted the extractor. While similar interrelations might be secured with other types of breech block, the transversely sliding breech block offers peculiarly favorable operative characteristics.

25. What is claimed is:—

1. An extractor mechanism comprising a lever having an extracting nose for engaging a cartridge case; a guide for said lever about which the lever pivots and relatively to which it is free to move radially; and a cam mechanism operable to shift said extractor radially to cause the nose to engage a cartridge, then swing it in an extracting direction, then withdraw it radially from engagement with the cartridge and then free the extractor to permit it to return to its initial position.

2. An extractor mechanism comprising a lever having an extracting nose for engaging a cartridge case; a guide for said lever about which the lever pivots and relatively to which it is free to move radially; and two cam mechanisms, one acting on said extractor lever to control its radial movement, and the other acting on the extractor lever to swing it in an extracting direction and then release it.

3. An extractor mechanism comprising a lever having an extracting nose for engaging a cartridge case; a guide for said lever about which the lever pivots and relatively to which it is free to move radially; and two sets of alternately acting cams mounted to rotate together, one functioning to cause it to engage and later disengage the cartridge case, and the other functioning intermediate the two movements just named and serving to swing the extractor in an extracting direction.

4. An extractor mechanism for firearms, comprising in combination, a reciprocable member formed with a plurality of cams; a breech block operable by certain of said cams; an extractor capable of motion to the rear and return; a star wheel mechanism operable by cams on said reciprocable member step-

by-step, each step in two stages which occur in relatively reverse movements of the reciprocable member; and cams rotated by said star wheel mechanism and arranged to force said extractor to the rear in the first stage of star wheel motion and release it in the second stage. 70

5. An extractor mechanism for firearms, comprising in combination, a reciprocable member formed with a plurality of cams; a breech block operable by certain of said cams; an extractor capable of motion to the rear and return; a star wheel mechanism operable by cams on said reciprocable member step-by-step, each step in two stages 75 which occur in relatively reverse movements of the reciprocable member; cams rotated by said star wheel mechanism and arranged to force said extractor to the rear in the first stage of star wheel motion and release it in the second stage; interlocking means between the breech block and extractor which obstruct the closing movement of the breech block while the extractor is in its rearward position; means actuated by said reciprocable member for chambering a cartridge; and means actuated during the final movement of said chambering means and serving to return the extractor to its forward position. 80

6. An extractor mechanism for firearms, comprising in combination, a reciprocable member formed with a plurality of cams; a breech block operable by certain of said cams; an extractor guided to move in a multi-sided path to engage, extract and clear a cartridge case, and then return to its initial 95 position; a star wheel operable by cams on said reciprocable member step-by-step, each step in two stages, the first and second stages occurring in relatively reverse movements 100 of said reciprocable member; and cams rotated by said star wheel and engaging said extractor to move the extractor to engage the case, then to the rear to extract the same and then away from the case in the first stage 105 of star wheel motion, and in the second stage 110 of star wheel motion, and in the second stage to free the extractor and permit its return to the initial position.

7. An extractor mechanism for firearms, comprising in combination, a reciprocable member formed with a plurality of cams; a breech block operable by certain of said cams; an extractor guided to move in a four sided path to engage, extract and clear a cartridge case, and then return to its initial 115 position; a star wheel operable by cams on said reciprocable member step-by-step, each step in two stages, the first and second stages occurring in relatively reverse movements of 120 said reciprocable member; cams rotated by said star wheel and engaging said extractor, to move the extractor to engage the case, then to the rear to extract the same, and then away from the case in the first stage of star wheel motion, and in the second stage to free 125

the extractor and permit its return to the initial position; interlocking means between the breech block and extractor which obstruct the closing movement of the breech block while the extractor is in its rearward position; means actuated by said reciprocable member for chambering a cartridge, and means actuated during the final movement of said chambering means and serving to return the extractor to its forward position.

8. An extractor mechanism for firearms, comprising in combination, a reciprocable member formed with a plurality of cams; a breech block operable by certain of said cams; a cartridge-case engaging member movable by said reciprocable member positively in a cartridge chambering direction and yieldingly in the reverse, cartridge-case ejecting direction; an extractor guided for motion in a multi-sided path to engage, extract and then clear a chambered cartridge; a star wheel operable by cams in said reciprocable member step-by-step, each step in two stages, the first and second stages occurring in relatively reverse movements of said reciprocable member; and cams rotated by said star wheel and engaging said extractor to move the extractor to engage the cartridge case, then to the rear to extract the same, and then away from the case, in the first stage of star wheel motion, and in the second stage of star wheel movement to free the extractor and permit its return to initial position.

9. An extractor mechanism for firearms, comprising in combination, a reciprocable member formed with a plurality of cams; a breech block operable by certain of said cams; a cartridge-case engaging member movable by said reciprocable member positively in a cartridge chambering direction and yieldingly in the reverse, cartridge-case ejecting direction; an extractor guided for motion in a multi-sided path to engage, extract, and then clear a chambered cartridge; a star wheel operable by cams on said reciprocable member step-by-step, each step in two stages, the first and second stages occurring in relatively reverse movements of said reciprocable member; cams rotated by said star wheel and engaging said extractor to move the extractor to engage the cartridge case, then to the rear to extract the same, and then away from the case, in the first stage of star wheel motion, and in the second stage of star wheel movement to free the extractor and permit its return to initial position; means on the extractor to latch the breech block against closing until the extractor returns to its initial position; and means operating in time with the cartridge-case engaging member to force the extractor to initial position upon the chambering of a cartridge.

10. A breech mechanism for firearms, comprising in combination, a barrel; a breech block mounted to slide transversely to said

barrel; a reciprocable action slide formed with a plurality of cams, certain of which engage and actuate said breech block in an opening direction; a spring urging said block in a closing direction; an extractor capable of motion to the rear and return; a star wheel mechanism operable by cams on said action slide step by step, each step in two stages which occur in relatively reverse movements of the action slide; cam means rotated by said star wheel mechanism and arranged to force said extractor to the rear in the first stage of star wheel motion and release it in the second stage; interlocking means between the breech block and the extractor which obstruct the closing movement of the breech block while the extractor is in its rearward position; a cartridge feeding rammer having a lost motion connection with said action slide, said rammer being arranged to engage the extractor on the final forward motion of the rammer and return the extractor to its forward position.

11. A breech mechanism for firearms, comprising in combination, a barrel; a breech block mounted to slide transversely to the barrel; a reciprocable action slide formed with a plurality of cams, certain of which engage said breech block and actuate the same in an opening direction; spring means urging said breech block in a closing direction; an extractor guided to move in a multi-sided path to engage, extract, and clear a cartridge case and then return to its initial position; a star wheel operable by cams on said reciprocable action slide step by step, each step in two stages, the first and second stages in relatively reverse movements of said action slide; and cams rotated by said star wheel and engaging said extractor to move the extractor to engage the case, then to the rear to extract the same, and then away from the case in the first stage of star wheel motion and in the second stage to free the extractor.

12. A breech mechanism for firearms, comprising in combination, a barrel; a breech block mounted to slide transversely to the barrel; a reciprocable action slide formed with a plurality of cams, certain of which engage said breech block and actuate the same in an opening direction; spring means urging said breech block in a closing direction; an extractor guided to move in a multi-sided path to engage, extract, and clear a cartridge case and then return to its initial position; a star wheel operable by cams on said reciprocable action slide step by step, each step in two stages, the first and second stages in relatively reverse movements of said action slide; cams rotated by said star wheel and engaging said extractor to move the extractor to engage the case, then to the rear to extract the same, and then away from the case in the first stage of star wheel motion and in the second stage to free the extractor; interengaging means

between the breech block and the extractor serving to obstruct the closing movement of the breech block while the extractor is in its rearward position and prevent rearward motion of the extractor until the breech block has reached its open position; and a cartridge feeding rammer having a lost motion connection with said action slide, the parts being so arranged that as the action slide reaches its forward limit of motion it forces the rammer into engagement with said extractor to shift the extractor to its forward position and free the breech block.

13. A breech mechanism for firearms, comprising in combination, a barrel; a breech block mounted to slide transversely to the barrel; a reciprocable action slide formed with a plurality of cams, certain of which engage said breech block and actuate the same in an opening direction; spring means urging said breech block in a closing direction; an extractor guided to move in a multi-sided path to engage, extract, and clear a cartridge case and then return to its initial position; a star wheel operable by cams on said reciprocable action slide step by step, each step in two stages, the first and second stage in relatively reverse movements of said action slide; cams rotated by said star wheel and engaging said extractor to move the extractor to engage the case, then to the rear to extract the same, and then away from the case in the first stage of star wheel motion and in the second stage to free the extractor; interengaging means between the breech block and the extractor serving to obstruct the closing movement of the breech block while the extractor is in its rearward position and prevent rearward motion of the extractor until the breech block has reached its open position; means actuated by said action slide for chambering a cartridge; and means actuated during the final movement of said chambering means and serving to return the extractor to its forward position.

14. A breech mechanism for firearms, comprising in combination, a barrel; a breech block mounted to move transversely to the barrel; a reciprocable action slide formed with a plurality of cams, certain of which engage said breech block and actuate it in an opening direction; a spring urging said breech block in a closing direction; a rammer having a lost motion driving connection with said action slide; a spring interposed between said action slide and the rammer urging said rammer rearward relatively to said slide whereby the rammer is actuated yieldingly in its rearward motion and positively in its forward motion; a hook mounted on said rammer for engaging the cannelure or rim of a cartridge case; a lug mounted on said rammer and adapted to engage and force a cartridge into the chamber of the barrel; an extractor guided to move to the rear and return; a star wheel mechanism operated by cams on said

action slide, step by step, each step in two stages which occur in relatively reverse movements of the action slide; means rotated by said star wheel mechanism and arranged to force said extractor to the rear in the first stage of star wheel motion and release it in the second stage; means on the extractor to latch the breech block against closing until the extractor returns to its initial position; and means associated with the rammer adapted to restore the extractor to such initial position as the rammer completes the chambering of a cartridge.

15. A breech mechanism for firearms, comprising in combination, a barrel; a breech block mounted to move transversely to the barrel; a reciprocable action slide formed with a plurality of cams, certain of which engage said breech block and actuate it in an opening direction; a spring urging said breech block in a closing direction; a rammer having a lost motion driving connection with said action slide; a spring interposed between said action slide and the rammer urging said rammer rearward relatively to said slide whereby the rammer is actuated yieldingly in its rearward motion and positively in its forward motion; a hook mounted on said rammer for engaging the cannelure or rim of a cartridge case; a lug mounted on said rammer and adapted to engage and force a cartridge into the chamber of the barrel; an extractor guided for motion in a multisided path to engage, extract and then clear the chambered cartridge; a star wheel operable by cams on said reciprocable member step by step, each step in two stages, the first and second stages occurring in relatively reverse movements of said reciprocable member; cams rotated by said star wheel and engaging said extractor to move the extractor to engage the cartridge case, then to the rear to extract the same, and then away from the case in the first stage of star wheel motion, and in the second stage of star wheel motion to free the extractor; means on the extractor to latch the breech block against closing until the extractor returns to its initial position; and means associated with the rammer adapted to restore the extractor to such initial position as the rammer completes the chambering of a cartridge.

16. The combination of claim 14, further characterized in that the lug on the rammer engages the cartridge case near the margin thereof only.

17. The combination of claim 15, further characterized in that the lug on the rammer engages the cartridge case near the margin thereof only.

18. The combination of claim 14, further characterized in that the breech block is formed with recesses on its forward face which extend part way through the block and

receive the lug and the cartridge engaging hook on the rammer.

19. The combination of claim 15, further characterized in that the cams on the action 5 slide which actuate the breech block permit this to move in a closing direction a short distance from its maximum open position as the action slide reaches its limit of motion and while the breech block and extractor are 10 interlocked whereby the breech block urges the extractor in a direction to free the cartridge case.

20. In a breech mechanism for firearms, the combination of a barrel; a breech block 15 mounted to slide transversely to the barrel; a reciprocable action slide formed with a plurality of cams, certain of which actuate said breech block in an opening direction; a spring urging said breech block in a closing 20 direction; a rammer movable by said reciprocable member positively in a cartridge-chambering direction and yieldingly in the reverse cartridge-ejecting direction; an extractor mounted to move toward and from the 25 rear; means actuated by the action slide for forcing said extractor positively to the rear in the initial excursion of the action slide, and to release said extractor upon the return excursion of the action slide; means on the 30 extractor to latch the breech block against closing while the extractor is in its rearward position; and means operated by the completion of the forward motion of the rammer for moving the extractor forward to unlatch the 35 breech block.

21. The combination of claim 20, further characterized in that said rammer is provided with a hook adapted to engage the rim or cannelure of a cartridge.

40 22. The combination of claim 20, further characterized in that the rammer is provided with a hook for engaging the rim or cannelure of a cartridge and with a lug for engaging the rear end of the cartridge case near 45 one margin thereof.

23. The combination of claim 20, further characterized in that the rammer is provided with a hook for engaging the rim or cannelure of a cartridge case and with a lug for engaging the rear end of a cartridge case adjacent one margin thereof, and that the breech block is formed on its forward face with recesses which receive said hook and lug.

24. The combination of claim 20, further 55 characterized in that the means which actuates the extractor comprises two sets of cams which urge the extractor first toward the cartridge to engage the same, then to the rear to extract the same, and then free the extractor to permit it to move away from the cartridge, and then to its initial position.

25. In a breech mechanism for firearms, the combination of a barrel; a breech block 60 mounted to slide transversely to the barrel; an extractor; a reciprocable action slide

formed with a plurality of cam means, certain of which actuate said breech block in an opening direction, and others of which actuate said extractor in an extracting direction, the breech block and the extractor being actuated 70 in timed relation; a spring urging said breech block in a closing direction; interlocking means between the breech block and extractor preventing the actuating of the extractor until the breech block is open, and preventing the closing motion of the breech block until the extractor is restored to its normal position; and means actuated by the action slide at the termination of its active excursion and serving to restore said extractor to 75 its normal position.

26. The combination of claim 25 in which the means which restores the extractor also serves to chamber a cartridge.

27. The combination of claim 25 in which 85 the means which restores the extractor is a reciprocating rammer having a lost motion connection with the action slide and having a yielding connection thereto, the rammer being provided with a lug which engages the 90 rear end of the cartridge to chamber the same and with a hook which engages the rim or cannelure of the cartridge to withdraw the case after the same has been freed by the extractor. 95

In testimony whereof I have signed my name to this specification.

CHARLES L. ROSS.
